United States Patent Office

Des. 181,590

Patented Dec. 3, 1957

181,590

CAMERA CARRYING CASE

Vincent F. Lang, Rochester, N. Y., assignor to Eastman
Kodak Company, Rochester, N. Y., a corporation of
New Jersey

Application February 18, 1957, Serial No. 44,896

Term of patent 7 years

(Cl. D61—1)

Fig. 1

Fig.2

Fig. 1 is a perspective view taken from one side of a camera carrying case embodying my new design with the camera carrying case in an open position;

Fig. 2 is a perspective view taken from a point beneath and from the same side of the camera carrying case of Fig. 1 with the camera carrying case in a closed position; and

Fig. 3 is a perspective view similar to Fig. 2 taken from a point above and from the other side of the camera carrying case.

I claim:

The ornamental design for a camera carrying case, as shown.
